DESIGN FOR A CARD-TABLE COVER

Vernon A. Davenport, Seattle, Wash.

Application November 14, 1938, Serial No. 81,073

Term of patent 7 years

To all whom it may concern:

Be it known that I, Vernon A. Davenport, a citizen of the United States, residing at Seattle, in the county of King and State of Washington, have invented a new, original, and ornamental Design for Card-Table Covers, of which the following is a specification, reference being had to the accompanying drawing, forming part thereof. The drawing is a view looking directly at the card-table cover, showing my new design.

I claim:

The ornamental design for a card-table cover, as shown.

VERNON A. DAVENPORT.
